UNITED STATES PATENT OFFICE.

JAMES L. HEELEY, OF ATTLEBOROUGH FALLS, MASSACHUSETTS.

DESIGN FOR AN ORNAMENTAL CHAIN-LINK.

SPECIFICATION forming part of Design No. 12,939, dated May 23, 1882.

Application filed April 22, 1880. Term of patent 7 years.

To all whom it may concern:

Be it known that I, JAMES L. HEELEY, a citizen of the United States, residing at Attleborough Falls, in the county of Bristol and State of Massachusetts, have invented and produced a new and original Design for Ornamental Chain-Links, of which the following is a specification, reference being had to the accompanying drawings, forming part thereof.

- 10 The nature of this design is fully represented in the accompanying drawings, in which—

Figure 1 shows a link in perspective view containing the same. Figs. 2 and 3 show modifications thereof.

- 15 Similar letters indicate corresponding parts.

The letter A designates a box constituting the essential feature of the link. This box has a polygonal cross-section, and in the angles thereof are notches b. In some cases the 20 notches b extend the whole length of the box

A, as shown in Fig. 1, and in others they are arranged near the opposite ends thereof, as shown in Fig. 2. Two box-sections having the notches b are also combined with intermediate ornaments, as shown in Fig. 3, without changing the character of my design. 25

What I claim as new, and desire to secure by Letters Patent, is—

The design for an ornamental chain-link, consisting of a box having a polygonal cross-section, and having notches in the angles thereof, as described, and shown in the accompanying drawings. 30

In testimony whereof I have hereunto set my hand and seal in the presence of two subscribing witnesses. 35
